(57) **CLAIM**

The ornamental design for an herb grinder, as shown and described.

DESCRIPTION

FIG. 1 is a perspective view of an herb grinder, showing my new design;

FIG. 2 is a top plan view thereof, which is identical to the bottom plan view;

FIG. 3 is a front elevational view thereof, which is identical to the rear elevational, right side elevational and left side elevational views;

FIG. 4 is a perspective view illustrating the herb grinder in an open configuration;

FIG. 5 is a top plan view thereof;

FIG. 6 is a bottom plan view thereof;

FIG. 7 is a front elevational view thereof, which is identical to the rear elevational view;

FIG. 8 is a left side elevational view thereof; and,

FIG. 9 is a right side elevational view thereof.

The broken lines in FIGS. 1-8 illustrate portions of the herb grinder that form no part of the claimed design.

1 Claim, 8 Drawing Sheets
